UNITED STATES PATENT OFFICE.

GEORGE ALLEN ROBERTS, OF PADUCAH, KENTUCKY.

FIRE ESCAPE

Application filed October 11, 1921. Serial No. 507,000.

To all whom it may concern:

Be it known that I, GEORGE ALLEN ROBERTS, a citizen of the United States, residing at Paducah, in the county of McCracken and State of Kentucky, have invented new and useful Improvements in Fire Escapes, of which the following is a specification.

This invention relates to improvements in fire escapes.

10 An object of the invention is to provide a simple and inexpensive device embodying novel features of construction whereby any number of persons may conveniently escape with perfect safety from a window of a 15 burning building.

Another object is to provide a light and durable device which may be folded to one side of a window casing when not in use and can be quickly adjusted at a moments notice to enable the occupants of a room to escape.

20 Another object is to provide a strong and efficient device which will support a rope or cable at a safe distance from the wall of 25 the building and prevent any injury to a person while descending to the ground.

With the above and other objects and advantages in view the invention consists in the novel construction, combination and arrangement of parts described and claimed.

In the drawings forming part of this application like numerals of reference indicate similar parts in the several views and wherein:

35 Figure 1 is a side elevation of the invention in open position and secured to a window casing of a building.

Figure 2 is a side elevation of the invention in folded position and secured to the 40 wall of a building.

Figure 3 is a top plan view of the invention in open position.

Figure 4 is a detail perspective view of the U-shaped supporting member.

45 Figure 5 is a detail perspective view of the vertical post.

Figure 6 is a detail perspective view of the brace rod.

50 Referring now particularly to the drawings, the numeral 10 indicates a pair of spaced metallic brackets which are removably secured to one side of a window casing 11 and are provided with aligned openings 12. A metallic post 13 is provided 55 with a transverse opening 15 adjacent to

its upper end which communicates with a centrally disposed longitudinal slot 14. A pair of pintles 16 project from the opposite ends of the post and are inserted in the openings 12 in the brackets.

60 A pair of plates 17 are secured to the opposite sides of the post at the lower end thereof and are provided with outstanding ears 18 having aligned openings 19 formed therein which receive a bolt 20 extending through a transverse opening 21 at the lower rounded end of a metallic brace rod 22.

65 The brace rod 22 is provided with a transverse opening 23 adjacent to its upper rounded end which receives a bolt 24 extending through aligned transverse openings 25 which are formed in the parallel arms of a U-shaped metallic supporting member 26. A bolt 27 extends through a pair of aligned transverse openings 28 at the inner end of 70 the supporting member. A pair of spaced lugs 30 project upwardly from the parallel arms of the supporting member and are adapted to engage a window sash 31 when the U-shaped member is moved to open position.

75 Another object is to provide a strong and efficient device which will support a rope or cable at a safe distance from the wall of 80 the building and prevent any injury to a person while descending to the ground.

85 A knob 37 is removably secured to the outer end of the supporting member and serves as a handle to facilitate the quick adjustment of the device.

90 An L-shaped hook 38 is removably secured to one side of the supporting member and retains the rope in coiled position when the device is not in use.

95 When the device is not being used, the bolt 27 is disengaged from the opening 15 100 in the post by means of the knob 37 whereupon the inner end of the supporting member moves downwardly to assume the folded position illustrated in Figure 2. The rope is coiled and placed upon the hook 38. However, when the device is to be used the window sash is raised and the rope is dropped out of the window. The knob 37 is then moved outwardly, thus raising the inner end 105 of the supporting member until the bolt 27 110

engages the opening 15. The window sash of the brackets, a pair of plates each being secured to the opposite sides of the post at the lower end thereof, outstanding ears 25 as to retain the device in position.

While it is believed that from the foregoing description and a study of the drawings that the nature and advantages of the invention will be readily apparent, I desire to have it understood that I do not limit myself to what is herein shown and described 10 and that such changes may be resorted to when desired as fall within the scope of what is claimed.

What I claim is:

In combination with a window sash and 15 casing, of a pair of spaced metallic brackets secured to one side of the casing and having aligned openings therein; a metallic post having an opening adjacent its upper end which communicates with a centrally disposed longitudinal slot, a pair of pintles 20 projecting from the opposite ends of said post and arranged in the respective openings of the brackets, a pair of plates each being secured to the opposite sides of the post at the lower end thereof, outstanding ears 25 formed on the plates and being provided with aligned openings, a metallic brace rod pivotedly secured at one end between the ears, a U-shaped supporting member pivotedly secured adjacent one end to the opposite end of the brace rod, a bolt carried by the spaced ends of the arms of the U-shaped member and being adapted to travel in the longitudinal slot in the post to engage the opening; a lug projecting from each arm of 30 the U-shaped member and being adapted to engage a side of the window sash; a cable connected to the free end of the U-shaped member, a link secured to the U-shaped member to receive the cable and a plurality of 40 spaced balls carried by the cable for the purpose specified.

In testimony whereof I affix my signature.

GEORGE ALLEN ROBERTS
